(57) **CLAIM**

The ornamental design for a dog bowl assembly, as shown and described.

DESCRIPTION

FIG. 1 depicts an exploded side perspective view of a dog bowl assembly, showing my new design.

FIG. 2 depicts a side perspective view of a first component of the dog bowl assembly.

FIG. 3 depicts a side elevation view thereof.

FIG. 4 depicts a top view thereof.

FIG. 5 depicts a bottom view thereof.

FIG. 6 depicts a side perspective view of a first part of the first component of the dog bowl assembly.

FIG. 7 depicts a side perspective view of a second part of the first component of the dog bowl assembly.

FIG. 8 depicts a side perspective view of a third part of the first component of the dog bowl assembly.

FIG. 9 depicts a side elevation view thereof.

FIG. 10 depicts a top view thereof.

FIG. 11 depicts a bottom view thereof.

FIG. 12 depicts a side perspective view of a fourth part of the first component of the dog bowl assembly.

FIG. 13 depicts a side perspective view of a fifth part of the first component of the dog bowl assembly.

FIG. 14 depicts a side perspective view of a second component of the dog bowl assembly, which is interchangeable with the third part of the first component of the dog bowl assembly shown in FIG. 8.

FIG. 15 depicts a side elevation view thereof; and,

FIG. 16 depicts a top view thereof.

The broken lines shown in the drawing illustrate portions of the dog bowl assembly that form no part of the claimed design.
